UNITED STATES PATENT OFFICE.

WILLIAM BECKER, OF CHICAGO, ILLINOIS.

GUITAR.

SPECIFICATION forming part of Letters Patent No. 493,810, dated March 21, 1893.

Application filed March 26, 1892. Serial No. 426,501. (No model.)

To all whom it may concern:

Be it known that I, WILLIAM BECKER, a citizen of the United States, residing at Chicago, in the county of Cook and State of Illinois, 5 have invented a new and useful Improvement in Guitars, of which the following is a specification.

Prior to my invention it has been usual to permanently secure the bridge to the face of 10 a guitar, and to provide a series of holes extending down through the bridge and guitar-face so as to permit the knotted ends of the strings to be introduced through the holes which are then temporarily plugged with pins. 15 It has been proposed, however, as an improvement upon such arrangement to provide a guitar with a tail-piece for holding the strings. In some instances this tail-piece has been bent so as to lap the rear end of the guitar, and at 20 its forward end rigidly and permanently united with a bridge; but such arrangement is objectionable for the reason that either different lengths of bridge must be provided for 25 different sizes of guitars, or the bends must be formed at different points along the metal plate of which the bridge is formed. In other instances tail-pieces have been provided with bridges and adjustably connected with holders on the rear ends of the instruments; in 30 other instances the tail-pieces have been made of wire and provided with bridges adjustably held by nuts on threaded arms or prongs of the tail-pieces, and in other cases the bridge has been permanently secured to the face of 35 the guitar at a point forward of the tail-piece, and provided with separately movable string rests for the purpose of changing the tones of the strings by separately adjusting the rests, which said arrangements are, however, complicated and involve the provision of parts 40 which are liable to work or wear loose and rattle.

The objects of my invention are to provide a commercially successful arrangement adapted 45 for application to guitars of different sizes already in use, as well as to new guitars; to do away with complicated devices; and to permit one length of tail-piece to answer for guitars of different sizes.

To the attainment of the foregoing and other useful ends, my invention consists in providing the guitar with the simplest form

of tail-piece for holding the strings, and arranging in front of such tail-piece the simplest form of bridge arranged to slide upon 55 the face of the guitar, and to such end having a broad, flat base, which rests upon the guitar and which can be adjusted along the same with reference to the size of the instrument. 60

In the accompanying drawings, Figure 1 represents in plan a guitar provided with my improved arrangement of shifting bridge and tail-piece, the adjustment of the bridge being illustrated in dotted lines. Fig. 2 is a section 65 taken centrally and longitudinally through a portion of the body of the instrument. Fig. 3 represents the bridge. Fig. 4 is a bottom plan view of the bridge.

A indicates the body of the guitar, B its 70 neck, C the set of tuning-keys and I the set of strings, said members being the ordinary parts of a guitar, and of the usual construction.

The tail-piece D, consists simply of a metal 75 plate bent near one end so as to provide it with a downwardly projecting rear end portion d adapted for application to the rear or tail end of the body of a guitar, the forward end of the metal plate being adapted for holding the knotted ends of the six guitar strings, and for such purpose being simply perforated to receive the strings and bent over in part cylindrical form as at d' so as to conceal the 80 knots. 85

The bridge E can be of wood, bone, metal or of any suitable composition, and consists simply of an oblong block having along its top a bearing e for the strings, and having a flat and comparatively broad bottom e' adapted to rest and slide upon the face or sound-board a of the guitar. The strings pass from the tail-piece to the keys and rest upon the movable bridge, which latter is held in place simply by the pressure of the strings under 95 tension, and hence said bridge can be shifted over the sound board with reference to the size of the guitar and required pitch. The tail-piece bears upon the body of the guitar at its bend d² and short downwardly extending rear portion d. The tension of the strings serves to raise the forward portion of the tail-piece from the sound board, and in thus relieving the sound board of this portion of the 100

tail piece I attain a better tone than where the tail-piece lies flat upon the same.

I am aware that banjos are provided with tail-pieces to which the strings are attached, 5 and with thin wooden bridges which are held upon their parchment heads by the strings, but I am not aware that prior to my invention it has been contemplated to provide a guitar with a tail-piece and a movable bridge 10 as herein described, and that my proposed arrangement may even seem somewhat impractical until tested. I have, however, practically and thoroughly tested the same and find it to be a highly advantageous and desirable arrangement.

By my invention one form and length of bridge will answer for guitars of all sizes; the sound board is relieved of the deadening 15 effect of a tail-piece resting along the same; the use of glue or screws for securing the

bridge is obviated; the bridge can be readily adjusted along the sound board according to need; the use for holes and keys is dispensed with; and the adjustment of the bridge relatively to the tail-piece attained in a simplified 25 way.

What I claim as my invention is—

A guitar provided with a tail-piece to which the strings are attached, and a bridge E provided with a bearing e for the strings, and a 30 broad flat bottom e', and made and arranged separate from the tail-piece and applied to slide upon the sound-board of the guitar whereon it is held in its adjustment by the pressure of the strings, substantially as and 35 for the purpose described.

WILLIAM BECKER.
